UNITED STATES PATENT OFFICE.

STILLMAN W. ROBINSON, OF COLUMBUS, OHIO, ASSIGNOR TO THE WIRE GRIP FASTENING COMPANY, OF CHICAGO, ILLINOIS.

MACHINE FOR INSERTING SCREW-THREADED WIRE.

SPECIFICATION forming part of Letters Patent No. 554,200, dated February 4, 1896.

Application filed March 19, 1895. Serial No. 542,308. (No model.)

To all whom it may concern:

Be it known that I, STILLMAN W. ROBINSON, of Columbus, county of Franklin, State of Ohio, have invented an Improvement in Machines for Inserting Screw-Threaded Wire, of which the following description, in connection with the accompanying drawings, is a specification, like letters and numerals on the drawings representing like parts.

10 This invention has for its object the production of an improved machine for inserting screw-threaded wire into soles, &c., in the manufacture of boots and shoes and other work.

15 In the machine to be herein described the end of a wire is screwed into the "stock," the term used to designate the leather of the sole or other work, and is then cut off to produce a fastening, each fastening being made of just

20 the proper length for the thickness of the stock at the point where the same is to be united, variations in length of fastenings being automatically determined, as will be hereinafter described.

25 I have provided novel means whereby the feed movement of the wire being screwed into the stock is made positive and substantially uniform while entering the stock, and then the wire-feeding spindle is raised 30 quickly, and to effect this I employ non-circular gearing.

35 I have mounted one of the two feed-rolls at the lower end of the rotating hollow spindle in a movable part or frame having combined with it a suitable spring whereby the degree of pressure with which the feed-rolls grasp the wire may be adjusted. I have also mounted the wire-feeding wheels in a novel manner, whereby they are enabled to run with a 40 minimum of friction. I have also mounted the hollow rotating wire-carrying spindle in bearings which are free to tip or oscillate somewhat, as may be required, to prevent the undue friction and heating of the spindle 45 when being rotated rapidly.

One part of my invention consists in a rotatable spindle provided with a two-part head, feeding-wheels mounted in said head, and a spring acting on one part of said head to hold 50 its feed-wheel in a yielding manner toward the feed-wheel of the other part of said head,

substantially as will be described; also, in a machine for inserting screw-threaded wire, means to support the work, a wire-carrying spindle supported at its upper end in a bearing and provided below said bearing with a fixed collar, a bearing to sustain said collar, and a cross-head to sustain said bearing, combined with a lever to reciprocate said cross-head to lift said bearing and spindle, and 55 means to rotate said spindle; also, in the cutter-carrying levers having arms provided with toothed sectors, and a threaded block engaged by and between said sectors, combined with an upright shaft having a quick 60 thread to engage said block.

Other features of my invention will be hereinafter described in the specification and particularly pointed out in the claims.

Figure 1, in front elevation, represents the 70 upper part of the machine containing my present improvements, a portion of the framework and other parts being partially broken out to show parts behind; Fig. 1^a, a detail to show part of the apparatus for actuating the wire-cutting mechanism; Fig. 2, a left-hand side elevation of the machine shown in Fig. 1. Fig. 2^a shows part of the gear d³ and some of its holes d²⁹. Fig. 3 is a section below the line x, chiefly to show the non-circular gears and compound eccentric actuated by or through them to effect the feeding of the wire and the raising and lowering of the spindle; Fig. 3^a, 75 a detail of the outer or ring-like part 6 of the compound eccentric. Fig. 4 is a sectional 80 detail showing the head at the lower end of the revolving hollow wire-carrying spindle through which the wire is fed by the feed-rolls. Fig. 5 is a section in the line x', Fig. 4, the line x² showing the line of section for 85 Fig. 4. Fig. 6 is a detail showing part of the wire-cutting mechanism; Fig. 7, details of the clutch mechanism to be described; Fig. 8, a detail of the annular multoothed pawl, shown also in Figs. 4 and 5; Fig. 9, a sectional 90 detail in the line x³, Fig. 5. Fig. 10 is a top view of the wire-holder fixed to the upper end of the spindle, and Fig. 11 is a section of Fig. 10 in the dotted line y y.

The framework or column A of the machine, said column having in practice feet to rest upon the floor, is and may be of suitable

shape to sustain the various working parts to be described. The framework has at its upper end a suitable chamber, in which is placed a box A', having at its exterior a semi-spherical or ball-like projection or enlargement resting on a semispherical seat A^X, said box receiving within it and serving as a bearing for the hollow spindle B, the box being free to tip or oscillate to compensate for gyroscopic motions or vibrations of the spindle when being run rapidly.

The upper end of the box A' is enlarged and hollowed out to constitute an oil-well, in which is placed suitable lubricating material.

The upper end of the spindle has fast on it a pulley B²⁰⁰, driven continuously from any suitable shaft, all the motions of the various different working parts being derived from said spindle. The pulley B²⁰⁰ has a top flange, B²¹, provided with suitable ears B²², to which are connected by suitable bolts B²³ ears B²⁴ of a wire-holder B²⁵, the said ears having, as shown, slots with large ends B²⁶ to fit easily over the bolts, the said slots enabling the holder to be removed without moving the bolts. The wire-holder B²⁵ is open at its lower side to receive therein the coil of wire, which is held in place by a plate B³⁰⁰, (see Fig. 11,) detachably secured to the holder by suitable ears, as B³⁰¹, or in any other suitable manner, the periphery of the plate having enlarged portions B³⁰³ to be brought into engagement with the ears by slight rotation of the plate, maintaining it in position. A central opening, B³⁰², in the plate permits the passage of the wire therethrough, the plate resting on the ears B²². By this construction the operator is enabled to place the coil of wire in the holder B²⁵ when removed from the machine and turned upside down, and the plate B³⁰⁰ is then applied and secured, after which the ties of the coil are removed, and the coil is thus retained in the holder when turned over and placed on the machine.

The holder lies flat with the axis of the coil of wire coinciding with the wire-receiving hole of the spindle, and the pulley-space between the holder and the spindle is cut away to provide a conical passage in which the wire may gyrate as the latter is drawn from the central opening of the coil of wire without rotating the latter relative to the spindle. The wire w will be led from said holder or coil down through the center of the spindle, all as required in screw-wire machines of the class upon which this is intended as an improvement, the coil of wire rotating continuously with the spindle as the wire is being consumed in the machine.

The lower end of the spindle B has (see Fig. 4) a two-part yoke or head B⁰ and B^X, the part B^X being mounted upon the part B⁰ by pivot a, the upper end of the part B^X being shaped to receive loosely a suitable spring a', preferably made as a washer, which at its center receives the head of a stud-screw a², a collar a³ of the stud-screw acting against

the inner side of the spring, (see Fig. 4,) the stud-screw entering a threaded hole in the block a⁴ attached to the part B⁰ of the head, 70 the rotation of said stud-screw in one or the other direction causing it to act with greater or less force upon said spring, and consequently pressing the lower end of the part B^X of the head toward the part B⁰. 75

The head referred to has screwed into it three sets of bearings B⁷, all substantially alike, said bearings being represented (see Fig. 5) as screws chambered at their inner ends to constitute oil-cups, said cups receiving loosely the ends of the axles B², B³ and B^{6X}, the chambers in the sleeve-bearings being large and deep enough to retain oil and keep said axles well lubricated, the oil being retained in the chambers or cups by centrifugal force. The axles B² and B^{6X} are mounted in the part B⁰ of the head and the axle B³ in the part B^X of the head. The axle B² receives upon it the feed-wheel B⁴ and the axle B³ the feed-wheel B⁵, while the axle B^{6X} receives upon it the long sleeve-like extension a²⁰ from the ratchet-wheel B¹⁵. The feed-wheel B⁴ has a sleeve-like hub B' projecting from it in each direction, and one end of the hub has fixed to it a pinion B⁹, which engages a pinion B¹⁰ (see Fig. 9) fast on a like sleeve-hub of the feed-wheel B⁵. The pinion B⁹ is engaged by an intermediate pinion B¹² (see Fig. 5) supported on a stud B¹³ carried by the part B⁰ of the head, the pinion B¹² being driven by a pinion B¹⁴, made, as herein shown, as a toothed ring (see Fig. 5) screwed onto the end of the long sleeve a²⁰ of the wheel B¹⁵ loose on the axle B^{6X}. The ratchet-wheel B¹⁵ is toothed at its periphery and also toothed at its inner side, as at c, (see Fig. 4,) the peripheral teeth being engaged by a suitable pawl B¹⁶, (shown by dotted lines, Fig. 4,) which acts to prevent retrograde rotation of said ratchet-wheel and also the pinion B¹⁴. 110

The sleeve a²⁰ of the ratchet-wheel B¹⁵ is surrounded loosely by a long sleeve-like pinion C, having at its periphery an annular groove to permit the wire w to pass said pinion, and said pinion is provided with an annular pawl C', made as a ring, having teeth at its side next said ratchet-wheel, said pawl being borne by a suitable spring C² against the teeth c at the inner side of the ratchet-wheel B¹⁵, the interior of the washer-shaped pawl being notched (see Fig. 8) to enable it to slide on and yet be moved by the teeth at the end of the pinion C. The pinion C is engaged by a toothed rack C³, grooved longitudinally opposite the annular groove of the pinion, said rack being fitted to slide up and down in a longitudinal groove cut in one side of the hollow spindle B, the rack being connected in suitable manner, as by screws a⁶, (see Fig. 4,) with a sleeve C⁶ having at its upper end (see Fig. 1) a flange 2, which rests on an inwardly-projecting flange of a ring 3, suitably attached to a ring 4, the two rings when suitably united, as by a screw-thread

or otherwise, (see Fig. 1,) being embraced by and seated loosely in a strap or yoke C⁸, having gimbal-journals, which are mounted in like arms of a bell-crank lever C⁹ pivoted at C¹⁰, upwardly-extended arms of said lever having fixed in them a pin 100 inserted loosely through holes in ears of an eccentric-strap C¹³, which surrounds a compound or two-part eccentric 5 6, the part 5 (see Fig. 3) being made preferably as integral with the hub of the non-circular gear D, to be described, and the part 6 as an eccentric-ring, the said lever, the ring C⁸, and parts actuated thereby having a definite positive stroke with relation to the horn b²⁴, which remains at a constant height.

The rings 3 and 4 and the surrounding ring C⁸ constitute what in the claims I designate as a "strap" or "yoke."

The gear D is free to revolve on a stud 7, and has (see Fig. 3) a hole which is entered by a key 8, said key being adapted to enter either one of the two half-circular holes 10 12 made in the ring-like outer eccentric, 6, when (see Fig. 3^a) either one of said holes is opposite the half-hole in the eccentric 5, the adjustment of the ring-like eccentric 6 about the eccentric 5 enabling the spindle to be moved for a greater or less distance, as may be required, the key 8 entering the partial hole 12 in said eccentric 6 when the stock is thick and the partial hole 10 when the stock is thin, it having been found advantageous to provide for a longer or shorter stroke of the spindle to better adapt the machine for thick or thin work and to increase the number of screws inserted in a given time for this work.

The ring 4 has at its interior a semispherical seat (see Fig. 1) for a buffer-ring b, having a semispherical lower end to rest on said seat, the upper end of the buffer-ring being provided with a suitable leather or other washer b', on which rests loosely the central part of the main cross-head B²⁰ instrumental in sustaining the nose or presser plate b²¹ and the wire-cutting mechanism to be described.

The cross-head B²⁰ has ears b²⁰, to which by suitable set-screws are connected slide-rods b² b³, extended through suitable guides b⁴ b⁵, forming part of the framework, and at their lower ends said slide-rods have attached to them the auxiliary cross-head b²², to which in turn is attached the nose or presser plate b²¹, which rests upon the stock supported upon a horn b²⁴ in usual manner, said horn and nose-plate being common to United States Patent No. 325,274, dated September 1, 1885.

The cross-head B²⁰ is shown as having adjustably mounted upon it two standards b²⁵, to the upper ends of which are attached strong spiral springs b²⁶, the lower ends of said springs being shown as attached to ears of the lever c⁹, said springs normally acting to keep the presser-plate b²¹ seated on the stock and hold the cross-head b²⁰ toward the buffer-ring referred to. The cross-head

B²⁰ (see Fig. 1) has at its interior a semi-spherical seat 14, which receives and supports a semispherical projection 15 on a box 16, the latter serving as an additional bearing for the spindle B, the upper end of said box 16 being enlarged to form a cup 16^x to contain a suitable supply of oil.

The spindle B above the box 16 has fixed to it a collar b⁸, (best shown in Fig. 1,) it having at its under side a suitable lip or projection to enter a notch in a ring b⁴, which rests loosely on a suitable shoulder of the box 16, said collar and ring being thus gimbal-jointed one with relation to the other. The spindle B is made in two parts screwed together at 66, (see Fig. 1,) and at the junction of said parts I have added a ring 20, which contacts with the lower end of and keeps the box 16 up against the ring b⁴. The spindle B above collar b⁸ is cut to form or is provided with a long pinion 21, which engages the teeth of a gear d made fast to a pinion d' mounted loosely on a stud d² suitably connected to the framework. The pinion d' engages a gear d³, which is thus rotated continuously with the spindle B.

Just below the center of rotation of the gear d³ is a non-circular gear d⁴, (see Fig. 3,) which engages the non-circular gear D, and between the non-circular gear d⁴ and the gear d³ I have provided a clutch mechanism, which, when it is desired to start the nailing, may be made to couple the gear d⁴ with the gear d³, and which may be moved to release the gear d⁴ from the gear d³ when it is desired to stop the nailing to remove a shoe, or for other purposes.

The clutch device, as herein shown, consists essentially of a bolt d⁵, free to slide in a suitable hole in the hub of the non-circular gear d⁴, a suitable spring d²⁰ (see Fig. 7) acting normally to move said bolt in the direction to cause it to engage the continuously-rotating gear d³ above it, said bolt entering one or another of a series of holes d²⁹ in said gear. (See Fig. 2^a, where a part of said gear is shown.) The hub of the gear d⁴ is quite long and surrounds a fixed stud d⁶, and at its lower end (see Fig. 2) said hub has a suitable cam d⁷, to be hereinafter described, which serves to impart motion to the shoe-feeding mechanism. The bolt d⁵ has a projection d^{5x}, with which co-operates a clutch-releasing device d²² under the control of a suitable treadle (not shown) located at the floor, said treadle having connected to it a rod d⁸, (partially shown in Fig. 2,) which is extended up through a hole in the column A, and is connected at 102 to one arm of an elbow-lever d⁹, pivoted at d¹⁰ on the framework, said lever having a third upwardly-extended arm d¹², preferably forked, as shown by dotted lines in Fig. 2, to engage an arm d¹³ of the clutch-actuator, herein shown as a three-armed lever or rocker mounted on and so as to turn loosely about a vertical stud d¹⁵, said lever or rocker having other arms or projections d¹⁶ d¹⁷. (See

Fig. 3.) The arm d^{16} of the actuator (see Fig. 3) has pivoted on it an arresting device d^{23} , it having its inner or acting end provided with a hook or projection to engage the corner of a block d^{24} fast to the non-circular gear d^4 , as in Fig. 3, the parts shown in said figure being supposed to be in the position occupied by them when the wire-feeding and spindle-reciprocating devices are at rest, the 10 spindle, however, rotating and revolving the toothed gear d^3 , from which the bolt d^5 is withdrawn.

When the machine is at rest, as described, a spring d^{18} , connected to said arresting device d^{23} , acts to keep the latter in the position shown, and also to hold the clutch-actuator in such position that the releasing device d^{22} serves to depress the bolt d^5 against spring d^{20} . Now if the workman desires to start the 20 machine in operation to insert fastenings he will put his foot upon said treadle and turn the clutch-actuator about stud d^{15} so as to remove the releasing device laterally from contact with the said bolt, letting the spring d^{20} 25 act to move the bolt and project the same from the hub of the non-circular gear d^4 into one of a series of holes d^{29} in the continuously-rotating gear d^3 , and at the same time the arresting device is moved from engagement with the block d^{24} .

When the nailing is to be stopped the operator will remove his foot from the treadle and let the spring d^{18} , referred to, act and move the releasing device d^{22} toward the said bolt, so as to present the inclined part thereof (see detail Fig. 7) in the line of movement of the projection d^{5X} of the bolt d^5 as the latter travels with the gear d^4 , thus withdrawing said bolt from engagement with the gear d^3 . 35 The non-circular gear d^4 engages and drives the non-circular gear D , before referred to, having the compound eccentrics 5 6. These gears are made non-circular or shaped substantially as shown, in order that the spindle 45 B , when being moved downwardly, may travel at a uniform speed, the speed being adjusted to the pitch of the threads on the wire w , and also that the spindle may be returned quickly or make its upward stroke quickly 50 at a variable speed.

If the movement of the lever C^9 was produced by a crank or eccentric actuated by a shaft revolving at a uniform speed, the strap or yoke and its connected rack would have a 55 variable rate of descent as the crank traveled toward its so-called "dead-center," which is objectionable.

In order to complete with ease the rotation of the peculiar non-circular gears in either 60 direction of rotation, I have provided the gear d^4 at its under side with a tooth d^{4X} , (shown by dotted lines, Fig. 3,) which engages a tooth 24 of similar shape at the upper side of the non-circular gear D .

65 The position of the compound eccentric shown is right for the long stroke of the machine. For the short stroke the part 6 of the

compound eccentric must be turned half-way around, and the pinion d' must be changed for a larger one, which necessitates another 70 position for the stud d^2 in the frame A , and for this change I have provided a second hole d^9 . (See Fig. 2.)

The gear D is provided with a cam projection 25, which at each rotation of said 75 gear strikes a wing 26 at the upper end of a rod 27, (shown separately in Fig. 6,) it having multiple-threaded portions 28 and 30, or portion provided with two or more screw-threads of long pitch to facilitate quick 80 action of the threads with a long throw of the parts moved thereby and with but little rotation of said rod. The threaded part 28 enters a suitable threaded bearing 29 fixed in the framework, and the threaded part 30 engages 85 a screw-thread in a rack-block 31. As the rod 27 is rocked, it is moved quickly vertically in its bearings, and at the same time the threaded part 30, in engagement with the rack-block 31, lifts the latter quickly, so that 90 its external teeth, in engagement with the toothed arms 32 of the rocking levers 33, (see Figs. 1^a and 2,) move said levers quickly about the studs 34, upon which they are mounted, said studs being sustained in suitable 95 ears of the auxiliary cross-head b^{22} , before referred to. Suitable ears of the rocking levers 33 receive removable pivots 36, on which are mounted carriers 37, which receive and hold the shanks of the cutters or chisels 100 38, which act to cut off the wire close to the surface of the stock after said wire shall have been screwed into the stock and through the same to the horn, said cutters or chisels being free to slide in diagonal holes made in 105 the nose-plate b^{21} resting, as described, on the stock.

As before stated, the upper or main cross-head, B^{20} , is kept seated when the nose-plate is off the work, but in a yielding manner, upon 110 the buffer-ring and during the descent of the spindle as the latter is being moved down by the elbow-lever C^9 . As soon as the nose-plate meets the stock resting on the horn, the further descent of the cross-head B^{20} is arrested, 115 but the elbow-lever C^9 continues to move, and in its further movement depresses or lowers the sleeve C^6 having the rack-bar C^3 , and causes the latter, in engagement with the pinion C , to rotate the wire-feeding wheels 120 grasping the wire between them, causing said wheels to feed the wire out from the head into the stock below the nose-plate.

The foot-lift D^5 , the sleeve D^4 to which it is attached, the stud D^3 on which it is adjustable vertically, the sole-feeding bar m free to be slid back and forth in a rocking block mounted on an arm D^2 , said feeding-bar being moved forward to engage the edge of the sole by a cam-finger h^4 of a depending leg or 125 link pivoted on the lever for moving the spindle up and down are and may be all substantially as in United States Patent No. 447,358, dated March 3, 1891. In this present inven-

tion the feeding movement of the bar m is effected by the cam projection d^7 , before referred to, moving in unison with the non-circular gear d^4 , it acting (see Fig. 2) on a projection t of an arm t' fast on a rock-shaft t^2 , having at its lower end a finger t^6 , which, as the shaft t^2 is moved to push the finger against the feed-bar m , effects the feeding movement thereof, a spring t^4 , connected to said feed-bar (see Fig. 2) and to a fixed part of the frame, (see Fig. 1,) restoring said feed-bar to its starting-point against a stop t^5 .

Having described my invention, what I claim as new, and desire to secure by Letters 15 Patent, is—

1. In a machine for inserting screw-threaded wire, a rotatable spindle provided with a two-part head, feeding-wheels mounted in said head, and a spring acting on one part of 20 said head to hold its feed-wheel in a yielding manner toward the feed-wheel of the other part of said head, substantially as described.

2. The rotatable spindle, its feed-wheels, and a shaft having a gear-wheel and a ratchet-wheel, combined with a wheel surrounding said shaft and provided with an annular pawl to engage said ratchet-wheel, and a rack to move said shaft and pawl, substantially as described.

3. Means to support the work; a wire-carrying spindle supported near its upper end in a bearing, and provided below said bearing with a fixed collar; a bearing to sustain said collar; and a cross-head to sustain said bearing, combined with a lever, a strap or yoke movable thereby through a definite stroke to reciprocate said cross-head to lift said bearing and spindle, and means to rotate said spindle, substantially as described.

4. In a machine for inserting screw-threaded wire, a rotatable spindle provided with wire-feeding devices, and having an attached ring, a box supporting said ring, and a collar fixed to said spindle, combined with a cross-head having a seat to support said box loosely, substantially as described.

5. The cutter-carrying levers having arms provided with toothed sectors, and a threaded block engaged by said sectors, combined with 50 an upright shaft having a quick thread to engage said block, substantially as described.

6. The cutter-carrying levers having arms provided with toothed sectors, and a threaded block engaged by said sectors, combined with 55 an upright shaft having a quick thread to engage said block, and having a second threaded part above it, a threaded box for said second threaded part, and means to rotate said shaft, substantially as described.

7. The cutter-carrying levers having arms provided with toothed sectors, and a threaded block engaged by said sectors, combined with an upright shaft having a quick thread to engage said block, and with means to raise said 65 rod, substantially as described.

8. The rotating spindle, wire-feeding mechanism carried thereby, the sleeve C^6 , the yoke

embracing the said sleeve, and the lever C^9 , combined with the non-circular gears D and d^4 , and devices intermediate the said gear D and the said lever, to move the latter, substantially as described.

9. The combination with the non-circular gears employed in feeding the wire, and the revolving spindle and intermediate actuating 75 devices, of clutch mechanism, as described, for stopping and starting the nailing while the spindle continues its rotation, substantially as described.

10. The combination with the rotating wire-carrying spindle and feed-wheels, of bearings screwed into the head of the spindle and having deep chambers for the reception of the axles of the feed-wheels, said bearings retaining oil and keeping the feed-wheel axles 80 lubricated, substantially as described.

11. The wire-carrying spindle, the lever to actuate it, connections between said lever and said spindle, the eccentric-strap connected to said lever, an adjustable two-part eccentric, 90 a non-circular gear to which said eccentric is attached, and gearing between said non-circular gear and said spindle whereby the stroke of the spindle may be varied, substantially as described.

12. The wire-carrying spindle, the box 16, the sleeve C^6 , a strap or yoke to sustain said sleeve, wire-feeding mechanism supported on said spindle, and devices between said sleeve and said feed mechanism to actuate the latter, 100 the lever C^9 jointed to said strap or yoke, the cross-head B^20 to sustain said box, and the connected nose-plate, combined with devices to move said lever and impart to said sleeve a definite positive stroke, substantially as described.

13. In a nailing-machine for uniting soles to uppers with screw-wire having threads of uniform pitch, a revolving spindle having wire-feeding mechanism, non-circular gears, 110 and mechanism actuated thereby to feed the wire at a uniform rate, and to then make the return stroke of the feeding mechanism quickly, substantially as described.

14. The wire-cutting-off chisels 38 sliding 115 by one end in the nose-plate, with the other end made fast adjustably in the chisel-carriers 37, and operated by the elbow-levers 33 engaging the rack-block 31, the latter working on the steep-threaded screw 27, as described.

15. In a screw-wire-nailing machine for fastening soles to uppers, the combination of the following instrumentalities, viz:—a work-supporting horn of constant height; a revolving 125 wire-carrying spindle supported on a cross-head connected to a nose-piece and adapted to be arrested as the nose-plate meets the stock on the horn, wire-feeding mechanism, a strap or yoke supporting said cross-head 130 when the latter is not resting by its nose-plate on the stock, mechanism connected with the said strap or yoke to impart to it a definite constant stroke, and devices between the

strap or yoke and the said wire-feeding mechanism, substantially as described.

16. Means to support the work, a wire-carrying spindle, a connected ring, a bearing to support said ring, a cross-head to sustain said bearing, a strap or yoke to sustain said cross-head, a sleeve connected to said strap or yoke, and a lever to move said strap or yoke, combined with wire-feeding mechanism, and devices intermediate said strap or yoke and wire-feeding mechanism to actuate the latter more or less during the descent of said strap or yoke according to the thickness of the stock, substantially as described.

17. The rotating wire-conveying spindle and its attached ring, the box 16, the strap C⁸, its attaching-lever, the two-part ring 2, 4, and the buffer-ring combined with the cross-head to sustain said box and spindle, substantially as described.

18. The spindle, its pivoted member B^X having a screw-hole and the spring a', combined with the screw a² extended through said spring and having a shoulder to engage the spring, substantially as described.

19. The gear d³, the gear D and the gear d⁴ provided with a sliding pin and mounted with relation to gear d³, combined with a releasing device and means to move it to control the said pin, substantially as described.

20. The gear D having a hub, an eccentric-ring surrounding said hub, and an eccentric-strap surrounding said ring combined with a pin to hold said ring in one of two positions on said hub, substantially as described. 35

21. The spindle and its attached pulley having a flaring opening at its upper side, combined with the covering-plate extending across the upper side of the coil of wire, and devices to connect portions of said covering-plate to the said pulley, said parts being arranged to present the open center of the coil of wire about the wire-passage in the spindle, substantially as described. 40

22. The spindle and its attached pulley having a flaring opening at its upper side, combined with a wire-holder having upper and lower annular retaining-plates to hold the wire and connected to the said pulley, and to present the open center of the coil of wire about the wire-passage in the spindle, substantially as described. 45

In testimony whereof I have signed my name to this specification in the presence of two subscribing witnesses.

STILLMAN W. ROBINSON.
